TOOTH PASTE DISPENSER WITH TENSION
MEANS FOR HOLDING THE TUBE IN POSITION

William H. De Moss, Childress, Tex.

Application April 9, 1948, Serial No. 20,020

1 Claim. (Cl. 222—100)

1
This invention relates to a dispensing apparatus, and is particularly adapted for dispensing toilet articles such as toothpaste or shaving cream from tubes that are flexible and collapsible in nature, it of course being understood that other kinds of paste carried in similar manner may be dispensed equally as well.

It is an object of the present invention to provide a collapsible tube dispensing device which is easily mounted on a wall or other support, and includes a housing for retaining the paste therein in position for dispensing at all times.

A further object of the invention is to so construct the housing that a winding key for compressing the tube contained therein may project externally of the housing to suitable apertured means and thereby allow the key to be turned as the contents of the tube in said housing diminishes.

Another object of the invention is to eliminate the necessity for manual operation of the tube with the attendant possibility of smearing or leaving the shaving cream or toothpaste around in the bathroom.

Yet another object of the invention is to provide tension means whereby the loosely fitting tube is retained in position within the container at all times and is always ready to be put into use.

And it is a further object of the invention to provide a dispenser that is durable in construction, pleasing to the eye, economical in manufacture and readily operated.

Many other objects and purposes will appear hereinafter from the following description taken in connection with the accompanying drawing, in which:

Figure 1 is a side elevation of the dispenser in position on a wall or other retaining means;

Figure 2 is a vertical section taken transversely through the dispenser as viewed on line 2—2 of Figure 1;

Figure 3 is a horizontal view of the dispenser and is taken substantially along the line 3—3 in Figure 1;

Figure 4 is a fractional sectional view similar to Figure 2 and is taken at right angles thereto; and

Figure 5 is a perspective view of the key means employed to reduce the size of the tube retained within the container.

Referring to the figures, the dispenser is indicated generally at 10 and is cylindrical in construction. Dispenser 10 is open at the top at 12 and is closed at the bottom thereof at 14, bottom 14 containing an annular aperture of consider-

able size 16 to receive the inverted head of a tube therein. A removable cover 18 is frictionally retained on cylinder 10, thereby closing it. While cover 18 has been shown as press-fit, it is obvious any other type of closure construction may be employed, such as threads or the like. Dispenser 10 includes a pair of oppositely disposed parallel aligned slots 20. Slots 20 extend from the open top of dispenser 10 and terminate a short distance above the bottom 14.

A tube 22, containing shaving cream or toothpaste or the like, is retained in inverted position within dispenser 10 so that the shoulders 24 thereof rest upon the perimeter of aperture 16 and the cap 26 thereof depends below bottom 14. A suitable key or spool 28 including the usual elongated slit 30 and thumb knob or finger-piece 32 extends transversely through slot 20 on cylinder 10 and retains within the slit 30 the upper end of tube 22, key 28 remaining in suspension by virtue of engagement with the comparatively rigid tube 22. A bracket 34 is secured by suitable bolts or the like 36 to a wall or other support, while the opposite end thereof contains an enlarged head 38 welded or otherwise secured to dispenser 10 on the outer surface thereof. Tube 22 is retained in position by means of flexible clips for springs 40 containing a lateral flange 42 riveted at 44 to the inner wall of container 10 and extending laterally in scroll formation 46 for engagement with the inverted end of tube 22. Thus, it is readily apparent that tube 22 is retained in position at all times while in dispenser 10.

As readily appears from the description above, cover 18 is removed and a tube to be used is inserted within the interior of dispenser 10 in inverted position, spring 40 serving to retain tube 22 in position for dispensing, with cap 26 extending beneath the bottom 14 through aperture 16. A spool or key 28 then engages the upper extremity of tube 22 and cover 18 is again replaced. When it is desired to remove the contents thereof, cap 26 is removed and spool 28 is given a slight turn by means of knob 32 to force a small portion of the contents thereof out of tube 22. Cap 26 is then replaced and the device is ready to be used again.

It is obvious that any material may be employed in the construction of the dispenser, such as a light metal, plastic, wood, or the like.

While this specification sets forth in detail the present and preferred construction of the device, it is to be understood that deviations may be resorted to and do not form a departure from the

spirit of the invention as defined by the appended claim.

Having described the invention, what is claimed as new is:

A dispenser for a tube having a neck portion comprising a substantially cylindrical hollow container open at its top end and having an aperture in its bottom wall for receiving the neck portion of the tube, diametrically opposed elongated slots in the side walls of said container, a key extending through said slots having a knob at one end disposed exteriorly of the container, and a longitudinal slit through said key for receiving the tube, and tension means carried interiorly of said container for retaining the tube in position in said container, said tension means including diametrically opposed spring clips secured interiorly of said container adjacent its bottom wall, said spring clips including scroll

portions adapted to bear against diametrically opposed portions of a tube adjacent its neck portion.

WILLIAM H. DE MOSS.
